UNITED STATES PATENT OFFICE.

CHARLES C. RUSSELL, OF CHICAGO, ILLINOIS.

AUTOMATIC CUT-OUT VALVE FOR SELF-PLAYING ORGANS.

1,400,240.

Specification of Letters Patent. Patented Dec. 13, 1921.

Application filed April 5, 1920. Serial No. 371,283.

To all whom it may concern:

Be it known that I, CHARLES C. RUSSELL, a citizen of the United States, and a resident of the city of Chicago, in the county of Cook 5 and the State of Illinois, have invented certain new and useful Improvements in Automatic Cut-Out Valves for Self-Playing Organs, of which the following is a specification, reference being had to the accompanying drawings, forming a part thereof.

The purpose of this invention is to provide an improved construction in a self-playing organ for arresting the playing action automatically when the note-sheet-propelling mechanism is adjusted for rewinding. 15 It consists in the elements and features of construction shown and described, as indicated by the claims.

In the drawings:

20 Figure 1 is a diagrammatic view showing conventionally the essential elements of an automatic organ in which the air passages are equipped with devices embodying this invention.

25 Fig. 2 is a detail plan view showing in conjunction with conventionally represented note - sheet - propelling motor and driving connections for playing and rewinding, the devices for shifting from playing to rewinding and the reverse and valve controlling 30 devices operated by said shifting devices which control the admission of air to the action chamber for playing.

There are represented in the drawings a 35 pumping means for producing partial vacuum comprising a motor, 1, and a pumper consisting of a plurality of crank-operated bellows, 2, 2, 2, 2; an exhaust air chamber, 3, which is connected by a trunk, 4, with 40 the pumping bellows and having spring-expanded air-receiving bellows, 3^a; the reed chamber, 5; the pneumatic action chamber, 6, said last mentioned chambers each being duplicated or consisting of two separate 45 parts indicated by the same reference numerals arranged at opposite sides of a fore-and-aft plane vertical through the instrument, one part pertaining to the lower half or bass of the playing-range of the instrument, and the other to the upper half or treble. 5^a, 5^a are ducts leading from the exhaust chamber to the two members, 5, 5, of the reed chamber. 7, 7, are air trunks leading from said exhaust chamber, 3, to the 55 two members, 6, 6, of the action chamber. 9 is designed to represent an air motor for

propelling the note sheet shown at 11, which is propelled in the familiar manner over a tracker board, 8, having ducts suitably connected with the primary pneumatics (not shown) in the pneumatic action chambers, 6, 6, for operating the playing devices represented by motor pneumatics, 10, which operate the reed-controlling valves in a manner requiring no specific explanation. The 60 means for shifting the drive connections of the air motor from one roll to the other, to change from winding for playing to rewinding, may be understood to be of any usual convenient construction, comprising 65 a re-wind-shift lever, 13, operated by a manually-accessible key, 16, said lever being shown in full line at playing position, and in dotted line at rewind position. The air trunks, 7, 7, which lead to the pneumatic 70 action chambers, 6, 6, respectively, branch from a main trunk, 20, leading directly from the exhaust air chamber, 3, the junction being effected by means of a T-fitting, 21, whose stem passage is connected with 75 the main trunk, 20, while its cross arm is connected at opposite ends with the trunks, 7, 7, respectively. 25 is a slide valve, operating piston-wise in the stem of the T-fitting, and thereabove across the lateral ports 80 leading into the two arms of the cross member of said fitting. The stem passage of said T-fitting is extended above the cross passage a short distance to afford guidance for the slide valve, 25, whose stem, 26, is 85 further guided at 27 above said fitting and is connected for operation of the valve by the moving wall, 28, of a motor pneumatic, 29, which collapses downward and thereby cooperates with the suction operating 90 through the trunk, 20, and the weight of the valve for holding the valve, 25, at closed position,—that is, cutting off communication of the exhaust chamber with the pneumatic action chambers, 6, 6, respectively, when 95 said motor pneumatic is put in communication with the exhaust chamber for collapsing it; and when said motor pneumatic is cut off from the exhaust connection and is free to expand under the action of its expansion spring, 28^a, it opposes the weight 100 of the valve, 25, lifting it for opening the same, and thereby opening communication from the exhaust chamber to the pneumatic action chamber, 5, 5. Said motor pneumatic, 28, is controlled for collapse and expansion in the manner indicated, by a 105 110

valved connection with the exhaust chamber, 3, consisting of the air trunk, 31, controlled by the valve, 32, which is carried upon a rod, 33, operatively connected with the shift lever, 13, which is shifted for changing the drive connection from playing to re-winding position, said valve being so positioned that it is moved to open position by the movement of the shift lever to re-wind position, at which position it is shown in dotted line in Fig. 2.

The result of the construction described, it will be readily understood, is that when the shift lever, 13, is at playing position, the 15 motor pneumatic, 29, is expanded by a spring and operated for holding the valve, 25, at open position, putting the pneumatic action chambers, 6, 6, in communication with the exhaust chamber for operating the pneumatic action for playing; but when the lever, 13, is shifted to re-wind position, opening the valve, 32, which controls the motor pneumatic, 29, causing the latter to be collapsed, the valve, 25, being released from the 25 upward pull of said pneumatic, is moved by the suction operating through the trunk, 20, to closed position cutting off communication of the exhaust chamber with the action chambers, 6, 6, and arresting the operation 30 of the pneumatic action and preventing playing while re-winding continues.

I claim:—

1. In a self-playing organ, in combination with the pumping means for producing partial vacuum, a receiving bellows in which a condition of partial vacuum is produced by the pumper, a pneumatic action chamber for controlling the playing; a conduit from the receiver to the pneumatic action chamber; a valve which controls the air connection with the pneumatic action chamber conduit mounted for movement to closed position in the direction of suction from the receiver; a suction-operated pneumatic 40 operatively connected with the valve for positively closing it by the collapse of the pneu-

matic, and positively opening it by the expansion of the pneumatic; a spring which tends to expand the pneumatic and open the valve against the suction; note-sheet-operating mechanism for winding and re-winding the note-sheet; means for reversing said mechanism from playing to rewinding, and connections from said means for controlling the suction connection of said pneumatic to 55 admit the suction at the rewinding position.

2. In a self-playing organ having suction-producing means for actuating the playing devices, a valve which controls the suction connection to the playing devices, mounted for movement to closed position in the direction of the note-sheet-operating mechanism, comprising means for reversing the direction of movement of the sheet for playing and re-winding respectively; connections operated by said means for causing the valve to be held open when said means is at playing position, and adapted to release it upon shifting to rewinding position, the playing devices comprising a pneumatic action chamber of two separate compartments, the air connection for controlling the same being forked or branched, a branch extending to each compartment, the valve being 60 slideable crosswise of the two branches intermediate the same at their point of branching from the main air trunk; whereby the movement of said valve produced by the suction in the main trunk is transverse to both the branches for closing the same by one movement.

3. In the construction defined in claim 1, the connection from the shifting means for holding the valve open, being a duct which controls the operation of said motor pneumatic and a valve which controls said duct operatively connected with the shifting lever.

In testimony whereof, I have hereunto set my hand at Chicago, Illinois, this first day 90 of April, 1920.

CHARLES C. RUSSELL.
